(57) **CLAIM**

We claim, the ornamental design for a display screen with animated graphical user interface, as shown and described.

DESCRIPTION

FIG. 1 is a first image in a sequence of a front elevation view of a display screen portion with icon showing our new design; FIG. 2 is a second image thereof; and, FIG. 3 is a third image thereof.

The appearance of the animated user interface sequentially transitions between the images shown in FIGS. 1-3. The process or period in which one image transitions to another forms no part of the claimed design. The broken line showing of the display screen portion is for the purpose of illustrating environmental structure and forms no part of the claimed design.
